UNITED STATES PATENT OFFICE.

I. C. EMEERY, OF BALTIMORE, MARYLAND, ASSIGNOR TO CHAPMAN SELF LOCKING NUT COMPANY, OF BALTIMORE, MARYLAND, TRUSTEES OF COMMON LAW ESTATE.

LOCK-NUT-PINCHING MACHINE.

Application filed January 30, 1923. Serial No. 615,904.

To all whom it may concern:

Be it known that I, I. C. EMERY, a citizen of the United States, residing at Baltimore, in the county of Baltimore and State of Maryland, have invented certain new and useful Improvements in Lock-Nut-Pinchng Machines; and I do hereby declare the following to be a full, clear, and exact description of the invention, such as will enable others skilled in the art to which it appertains to make and use the same.

This invention relates to machines for compressing or pinching slotted lock nuts, and has for its object to provide a mechanism which will be simple in construction, comparatively inexpensive to manufacture, and more efficient in use than those heretofore proposed.

With these and other objects in view, the invention consists in the novel parts and combinations of parts constituting the apparatus, more fully hereinafter disclosed and particularly pointed out in the claims.

25 Referring to the accompanying drawings forming a part of this specification, in which like numerals designate like parts in all the views:

Figure 1 is a front elevational view of a machine made in accordance with this invention;

Figure 2 is a plan view of the parts shown in Figure 1;

Figure 3 is a sectional view taken approximately on the line 3—3 of Figure 2, looking in the direction of the arrows;

Figure 4 is a detail perspective view of a nut supporting block;

40 Figure 5 is a plan view similar to Figure 2, but showing the nut compressing parts in section and in positions different from those illustrated in Figure 2;

Figure 6 is a sectional view similar to Figure 3, but showing the parts in an operative position similar to that shown in Figure 5; and

Figure 7 is a detail sectional view of the pivoted nut compressing parts disposed in a vertical position.

1 indicates any suitable frame work, 2 a power pulley mounted on the shaft 3 carries

ing the driving pinion 4 meshing with the driven gear 5, mounted on the shaft 6, provided with the eccentric 7, carrying the pin 8 actuating the connecting rod 9 pivoted as at 10 to the slideable member 11 reciprocating in the ways 12. To the member 11 is secured the plunger 13, adapted to reciprocate across the bottom of the chute 14, and to push out one at a time the nuts 15 carried by said chute. The supporting block 16 as best illustrated in Figures 3 and 4 forms the bottom of the chute 14 and is provided with the inclined surfaces 17 and 18 adapted to receive the edges of the displaced nuts, and these surfaces terminate in the horizontal flat surface 19 which supports said nuts as they rest in the chute 14. Mounted on the gear 5 is a cam 20, and slidingly mounted on the frame 1 as at 21 is a reciprocating rod or bar 22 having an upper edge 23 adapted to also temporarily support the nuts 15 immediately after they are pushed from the chute 14, and near said upper surface 23 the end of said bar 22 is beveled off as indicated at 24, Figure 3. The other end of said bar 22 is provided with a pin or bolt 25, and sleeve 26 surrounding said bolt, a roller 27, at the end of said sleeve, and a nut 28 to hold said roller in place.

As will be clear from Figure 2, the cam 20 as it revolves with the gear 5, strikes the roller 27, and thus moves said bar 22 in one direction while stretching the spring 29. After the cam 20 passes the roller 27 the stretched spring returns the bar 22 to its normal position. The supporting block 16 is provided with an extension 30 having an under surface 31 which overlies the bar 22 in its reciprocatory movements and further serves to hold and guide the bar 22 as it moves over the surface 32 of the frame member 1, all as will be plain from Figures 3 and 4.

Passing through the portion 33 of the frame 1 is the adjustable screw member 34 95 provided with the nut 35 and the collar like member 36 to which is attached one end 4 of the coiled springs 37, the other ends of which are secured to a collar or flange 38 carried by a hollow thimble or an- 100

vil like member 39 which is provided with a ball 40 against which fits a cone shaped tapered plug 41 as illustrated. The point of the cone 42 fits in a depression 43 with 5 which the screw member 34 is provided. The thimble or anvil like member 39 as well as the bolt 40 and cone shaped member 41 are thus supported entirely by the stiff coiled springs 37, and are enabled to swing in 10 all directions around the point 42 as a center. Said thimble like member 39 further in its normal position registers with the plunger 13, so that when the nuts 15 are forced out of the chute 14, they are forced 15 against the said thimble like member 39, because the screw 34 has been so adjusted as to cause the flat surface or bottom portion of the thimble like member 39 to contact with said nuts just before the plunger 20 13 has completed its stroke in the direction which forces said nuts out of the chute 14. Now, the lock nuts 15 are all provided with slots 45 and the purpose of this machine is to close said slots at their outer ends as illustrated in Figure 5, so that the threaded portions of the nuts on each side of the slots 45 will not be parallel to each other and will thus bite into the threads of the bolt to which they may be applied and cause a 25 firm locking action. On the other hand, as is well known, it is very difficult to get nuts of the character illustrated to pass down a chute and always present the extreme outer end of the slot at the very bottom 30 of the chute. In other words, as is well known the nuts in coming down the chute will have said extreme outer end turned in all sorts of directions, with the result that a plunger such as 13 would sometimes strike the nut in the proper position to close the slot as illustrated, while at other times it would strike another portion of the nut, and thus fail to function properly unless the nuts should all be carefully oriented 35 before the plunger acts upon them.

With this invention, on the other hand, the thimble 39 being pivoted around the point 42 as a center, it makes no difference how the nut 15 may be oriented or positioned with respect to the extreme end of the slot 45 at the bottom of the chute, for said nut will be jammed against the thimble or anvil 39, and said thimble will always 40 turn on its pivot 42 in such a way as to receive the pressure of the reciprocating plunger 13 in a direction suited to the proper closing of the slot 45. That is to say, when the extreme end 46 of the slot 45 happens to occupy its lowest position as is indicated 45 in Figure 5, then the thimble 39 automatically turns upwardly as illustrated in said figure, and the jaws of the nut are properly closed as shown. On the other hand, suppose the extreme end 46 of the slot 45 50 should be presented in a position 180° from

that shown in Figure 5. In that case, the thimble 39 would be turned downwardly as seen in said figure instead of upwardly and the jaws of the nut would be just as effectively closed. Should the extreme edge 55 46 of the slot 45 be turned through an angle of 90°, in an upward direction, as seen in Figure 5, then the thimble 39 would correspondingly be turned in a direction perpendicular to the plane of the paper, and the 60 nut would likewise be properly closed. The same remarks apply should the extreme edge 46 of the nut 45 be turned through an angle of 90° in a downward direction from the position shown in Figure 5. In other words, 65 a little consideration will show that no matter how the slotted nuts 15 may be presented at the bottom of the chute 14, the thimble or anvil 39 will in every case turn on its pivot 42 so as to cause the proper closure 70 of the jaws of the nuts 15.

The parts are so timed that the surface 23 of the rod 22 supports the nuts 15 during the action of closing the slots 45 in the manner above indicated, but as soon as 75 the plunger 13 recedes the rod 22 also recedes so that its inclined surface forms a continuation of the inclined surface 18 of the block 16 and thus permits the nut whose slot has been closed to drop by gravity down 80 past the inclined surface 46 of the frame 1, see Figures 3 and 6. A suitable receptacle not shown is provided for the nuts, whereupon they are ready for shipment and use.

It will now be clear that after screw 100 threaded nuts 15 have been provided by any suitable means with the slots 45 they may be fed in quantity to the chute 14, and may be permitted to reach the bottom of said chute in any haphazard positions, so long as the 105 slots 45 remain in a vertical plane. It will further be clear that the plunger 13 in its reciprocations first pushes out the bottom nut onto the surface 23 of the reciprocating rod 22 and compresses the jaws of said nut 110 together no matter in what direction the slot 45 of the nut may point, for the pivoted thimble 39 turns in such a direction as will present its full flat bottom portion to the flat 115 surface of the nut, and thus will the jaws be properly compressed to form a lock nut out of the slotted nuts 15.

It will further be clear that as soon as the compressing plunger 13 recedes from its compressing position, the rod 22 will recede 120 due to the action of the cam 20 on the roller 27 and the nut will thus be permitted to fall out of the machine down past the inclined surfaces 18, 24 and 46, as will be clear from Figure 6.

It is obvious that although this machine shows the thimble or anvil 39 as operating in a horizontal direction yet it is not at all necessary that it be so positioned. In Figure 7, the thimble 39 is illustrated as being 125

in a vertical position, when compared with Figure 6, and it is evident that any suitable reciprocating compressing means may coact with the thimble 39 in a vertical position, 5 as well as in a horizontal position. In fact, there is no necessity that the thimble 39 be oriented in any particular position. It will function satisfactorily whether it is inclined to the horizontal or not. It is further 10 evident that other mechanisms may be employed to provide a reciprocating plunger mechanism, the equivalent of the plunger 13, and therefore I do not wish to be limited to the above disclosure except as may be 15 required by the claims.

What I claim is:

1. In a machine for pinching slotted nuts the combination of means to support said nuts; a movable member adapted to apply 20 pressure to said nuts; and a pivoted member adapted to resist the applied pressure.

2. In a machine for compressing portions of slotted nuts, the combination of means capable of movement in horizontal and vertical directions adapted to receive pressure 25 from said nuts; and means to compress said nuts against said first named means.

3. In a machine for compressing portions of slotted nuts, the combination of means 30 to feed said nuts into positions to be compressed; a movable means to apply pressure to the fed nuts; and means capable of movement to one side of the direction of movement of said first named movable means adapted to receive pressure from the 35 compressed nuts.

4. In a machine for compressing portions of slotted nuts the combination of means comprising a chute to feed said nuts into positions to be compressed; a movable means 40 comprising a plunger to apply pressure to the fed nuts; and means comprising an anvil capable of movement to one side of the direction of movement of said first named movable means adapted to receive pressure from the 45 compressed nuts.

5. In a machine for compressing portions of slotted nuts, the combination of means 50 to feed said nuts into positions to be compressed; a movable means comprising a reciprocating plunger to apply pressure to the fed nuts; and means comprising a pivoted anvil capable of movement to one side of the direction of movement of said first named movable means adapted to receive pressure from the 55 compressed nuts.

6. In a machine for compressing portions of slotted articles, the combination of means 60 to hold said articles in positions to be compressed; means to apply pressure to said articles; and an anvil to receive the compression of said articles adapted for movement in two planes.

7. In a machine for compressing articles 65 having some portions more easily distorted

than others, the combination of means to supply the power to compress said articles; and an anvil to receive the compressive force applied to said articles, said anvil provided with means adapting it to automatically 70 so move during the compressive action as to cause the more easily distorted portions of said articles to receive the most compression.

8. In a machine for pinching slotted nuts, the combination of movable means to support said nuts; a reciprocating movable member adapted to apply pressure to said nuts; and a pivoted member adapted to resist the applied pressure. 75

9. In a machine for compressing portions of slotted nuts, the combination of means comprising an anvil capable of movement in horizontal and vertical directions adapted to receive pressure from said nuts; and power driven reciprocating means to compress said nuts against said first named means. 85

10. In a machine for compressing portions of slotted nuts the combination of means to feed by gravity said nuts into positions to be compressed; a reciprocating movable means to apply pressure to the fed nuts; and means comprising a pivoted anvil capable of movement to one side of the direction of movement of said first named movable means adapted to receive pressure from the compressed nuts. 90

11. In a machine for compressing portions of slotted articles, the combination of means comprising a reciprocating member to hold said articles in positions to be compressed; power driven reciprocating means to apply pressure to said articles; and an adjustable pivoted anvil to receive the compression of said articles adapted for movement in two planes. 95

12. In a machine for compressing slotted articles the combination of means to apply the compressive force to said articles; and a spring controlled anvil pivoted for movement to one side of the direction of the applied force adapted to receive said articles during their period of compression. 100

13. In a machine for compressing articles the combination of a power driven reciprocating plunger; means to automatically feed articles into position to be compressed by said plunger; and a pivoted adjustable anvil normally in line with said plunger adapted to receive said articles while being compressed but to be automatically partially deflected from said line when the compression of different parts of said articles are unequal. 115

14. In a machine for applying a compressive power to a slotted article the combination of means for supplying said power; a spring controlled anvil for receiving said article during its compression; and means for permitting said anvil to move in dif- 120

ferent directions when the compressive force is not uniform over its surface.

15. In a machine for applying a compressive power to a slotted article, the combination of means comprising a reciprocating plunger for supplying said power; a spring controlled anvil for receiving said article

during its compression; and means comprising a ball and a pivoting member for permitting said anvil to move in different 10 directions when the compressive force is not uniform over its surface.

In testimony whereof I affix my signature.

I. C. EMERY.
